CIRCUIT CONTROLLER

Grant A. Swanson, Spring Park, Minn.

Application September 1, 1950, Serial No. 182,869

1 Claim. (Cl. 137—780)

1

The invention herein presents an apparatus operable in response to differential in pressure and by reason of flow of fluid through the apparatus to close circuits for signs or writings to be illuminatively displayed and to equalization of pressure of fluid in said apparatus to cause said circuits to be opened.

The object of the invention is to provide an apparatus of new and improved construction for controlling circuits for signs or writings to be illuminated.

In the accompanying drawings forming a part of this specification,

Fig. 1 is a diagrammatic view of a circuit controlling apparatus made according to the invention;

Fig. 2 is an enlarged elevational view of the unit of the apparatus at the lower right in Fig. 1;

Fig. 3 is a plan view of the unit disclosed in Fig. 2;

Fig. 4 is a vertical sectional view, taken on line 4—4 in Fig. 3;

Fig. 5 is a view corresponding generally with the disclosure of Fig. 4, but showing parts in different positions;

Fig. 6 is an elevational view disclosing first and second solenoids of the apparatus and switches controlled thereby contained in the unit of the apparatus at the lower left in Fig. 1; and

Fig. 7 is a diagrammatic view of a wiring system for the apparatus.

As herein illustrated and described, the circuit controlling apparatus is operable to energize one or more illuminable signs or writings in response to differential in pressure and by reason of flow of a beverage, such, for example, as beer or coffee, from a source of supply thereof through the apparatus to a location for use, and to cause said signs or writings to be deenergized in response to equalization of pressure of fluid in said apparatus.

With respect to the drawings and the numerals of reference thereon, 10 denotes a first pipe to lead from a source of pressure supply (not shown) of a liquid beverage, and 11 represents a second pipe to lead to a tap (also not shown) from which the liquid beverage is to be withdrawn for use.

A frame of the apparatus, supporting a switch box 12 and first and second fluid conveying units, indicated 13 and 14, respectively, is constituted as an elongated element 15, upon which said switch box is secured, and spaced, transversely extending elements 16 and 17 integral or rigid with opposite ends of said elongated element and in facing relation to each other.

The first fluid conveying unit 13 consists of a first rigid tube 18 having its exterior end secured,

2

as at 19, in the transverse element 16 and its interior end secured, as at 20, to and in alined relation with a first bellows 21.

The second fluid conveying unit 14 consists of a second rigid tube 22 having its exterior end secured, as at 23, in the transverse element 17 and its interior end secured, as at 24, to and in alined relation with a second bellows 25.

The first pipe 10 leads, as at 26, into the first rigid tube 18 at a location interiorly of the transverse element 16, and the second pipe 11 leads, as at 27, out of the second rigid tube 22 at a location interiorly of the transverse element 17.

The first and second fluid conveying units 13 and 14 are in alined relation with the interior ends of the first and second bellows 21 and 25 adjacent each other.

The exterior ends of the first and second rigid tubes 18 and 22 are open to access ports, denoted 28 and 29, respectively, through the transverse elements 16 and 17, and externally threaded closure plugs, represented 30 and 31, respectively, are removably situated in internal threads bounding said access ports. The construction and arrangement are such that the closure plugs can be removed to render the interiors of the rigid tubes and bellows readily and easily accessible for cleaning purposes.

A movable arm 32, rigidly secured between the interior ends of and in perpendicular relation to the first and second bellows 21 and 25, includes an extension portion which projects through a rectilinear slot 33 in the elongated element 15 and supports a movable element or protuberance 34 disposed at the side of said elongated element 35 opposite the first and second fluid conveying units 13 and 14. Said interior ends of said first and second bellows are open to each other by way of a restricted orifice 35 through said movable arm 32.

Flow of fluid from the first pipe 10 to the second pipe 11 will be by way of the interior of the first conveying unit 13, the restricted orifice 35 and the second conveying unit 14.

The switch box 12 includes a push button 36 normally situated, as in Figs. 1 to 4 of the drawings, to permit a movable contact element 37 to be in spaced relation to a fixed contact element 38, and adapted to be depressed, as in Fig. 5, to cause said movable contact element 37 to engage said fixed contact element 38. That is, closing of the switch 37—38 is accomplished in response to movement of the arm 32 toward the left in the drawings, and opening movement of said switch is permitted when said arm 32 is moved toward the right.

The construction and arrangement will be such

that when the second pipe 11 is closed off, thus to cause pressure of fluid in the first and second conveying units to be equalized, the movable arm 32 will be situated to position the protuberance 34 at its farthest distance from the push button 36, toward the right in the drawings, and when said second pipe is open, thus to cause flow of fluid from the apparatus and pressure of fluid within the second conveying unit to be less than in the first conveying unit, the movable arm 32 will be moved, toward the left in said drawings, to depress said push button 36 and cause the switch 37-38 to be closed. Said switch 37-38 will remain closed as long as flow continues to cause pressure in the second conveying unit to be less than in the first conveying unit, and will become opened upon cessation of flow causing equalization of pressure in said first and second conveying units.

Separate signs or writings to be illuminated are shown as bulbs, designated 39, 40, 41 and 42, respectively.

An incoming wire 43 from a suitable source (not shown) of electrical energy extends by lead wires 44, 45, 46 and 57 to the bulbs 39, 40, 41 and 42, and lead wires 48, 49, 50 and 51 extend from said bulbs to equally spaced, fixed contact elements 52, 53, 54 and 55 of a compound switch, disclosed more clearly in Fig. 6, including a rotatably supported switch arm 56.

The switch arm 56 is connected by a lead wire 57 to one of spaced, fixed contact elements 58, 58 of a switch also including a movable contact element 59 adapted to bridge the fixed contact elements 58, 58, and an incoming wire 60 from said source of supply is connected to the other of said fixed contact elements 58.

A lead wire 61 extends from the incoming wire 43 to a first solenoid 62, for controlling the switch 58-59-58, a lead wire 63 extends from said first solenoid 62 to a second solenoid 64, for rotatably advancing or actuating the switch arm 56, a lead wire 65 extends from said second solenoid 64 to the fixed contact element 38, and a lead wire 66 connects the incoming wire 60 to the movable contact element 37.

Energization of the first solenoid 62 is adapted to cause the switch 58-59-58 to be closed, and deenergization of said first solenoid is adapted to cause said switch 58-59-58 to be open.

The switch arm 56 is fixedly supported upon an insulating disc 67 rotatably mounted, at 68, within a casing 69 of the apparatus. Said disc 67 suitably and conveniently supports actuator lugs 70, four as shown, supported at 90 degrees apart about the axis of the disc.

The second solenoid 64 also is supported in the casing 69. A lever 71 has an intermediate portion thereof pivoted, as at 72, upon said casing, and a short arm of said lever has a longitudinal slot in its outer end portion which slidable and rotatably receives a pin 73 rigid with the core 74 of the second solenoid 64.

The outer end of a long arm 75 of the lever 71, at the side of the pivotal connection 72 opposite the second solenoid 64, pivotally supports, as at 76, the midportion of an actuator bar 77 disposed in angular relation to said lever 71. An end portion of the actuator bar 77 adjacent the lever 71 is resiliently connected, as at 78, to an intermediate portion of said long arm 75 for limited swinging movement, and a beveled end 79 of said actuator bar, in spaced relation to said lever 71, is adapted to be successively engaged with the actuator lugs 70. The construction and arrange-

ment will be such that a tension spring 80 will retain the core 74 at its farthest distance from the second solenoid 64 when said second solenoid is deenergized, thus to retain the beveled end 79 of the actuator bar 77 at the rear of and in proximate relation to an actuator lug 70, and energization of the second solenoid will draw said core inwardly against resilient action of said tension spring, thus to cause said actuator bar to rotate the insulating disc 67 ahead one step. In Fig. 6 the core 74 is shown in its position as when the second solenoid 64 is energized, and the actuator bar 77 is disclosed as when it has completed a step advancement of the insulating disc 67. Upon deenergization of said second solenoid, the tension spring 80 is adapted to react to rotate the lever 71 in counterclockwise direction in said Fig. 6 to cause the long arm 75 of said lever and the actuator bar 77 to be swung downwardly, thus to cause said actuator bar to be moved to a receded position so that its beveled end 79 is positioned at the rear of and in proximate relation to the next succeeding actuator lug 70, situated to be capable of rotatably advancing the insulating disc 67 one step in response to an immediately succeeding energization of the second solenoid 64. The switch arm 56 normally is engaged with one or another of the fixed contact elements 52, 53, 54 or 55, and said switch arm is moved from engaged relation with a succeeding fixed contact element to engaged relation with the next preceding fixed contact element in response to each energization of said second solenoid.

Supposing the parts of the apparatus to be in their inoperative positions, as in Figs. 1 to 4 and 7 of the drawings, and beverage to be withdrawn from a tap controlling the second pipe 11, the movable arm 32 will be moved to the left in the drawings, in response to differential in pressure existing at the right and left sides of the orifice 35 and by reason of flow of liquid from the apparatus, to cause the protuberance 34 to depress the push button 36 thus to cause the switch 37-38 to be closed and retained in closed condition as long as liquid continues to flow from the apparatus.

Closing said switch 37-38 will complete a circuit through the first and second solenoids 62 and 64, said circuit being traced from the incoming wire 43 by the lead wire 61 to said first solenoid, thence by the lead wire 63 to the second solenoid, thence by the lead wire 65 to the switch 37-38, and thence by the lead wire 66 back to the incoming wire 60.

Energization of the first solenoid 62 will cause the switch 58-59-58 to be closed to complete a circuit including one of the bulbs, 39, 40, 41 or 42, as the case may be, said circuit being traced from the incoming wire 43 back to the incoming wire 60 by way of one of 44, 45, 46, 47, one of 52, 53, 54, 55-56-57-58-59-58, and the bulb connected in circuit will remain energized as long as there is flow of liquid from the apparatus. Said first solenoid will become deenergized concurrently with equalization of pressure in the first and second fluid conveying units 13 and 14 occurring when flow from the apparatus is terminated, and upon deenergization of the first solenoid, the switch 58-59-58 will open to break the bulb circuit.

Each energization of the second solenoid 64 will advance the switch arm 56 one step to cause said switch arm to engage the next preceding contact element, 52, 53, 54 or 55, as the case may be. The switch arm 56 will be advanced one

step to cause a different bulb circuit to be closed each time the first and second solenoids are simultaneously energized. Said switch arm 56 will remain engaged with the fixed contact element it is caused to engage in response to each actuation of the second solenoid until removed therefrom in response to a next succeeding actuation of said second solenoid. Each bulb circuit, however, includes the switch 58—59—58, as well as a fixed contact element of the compound switch having the switch arm 56, so the bulbs are incapable of being energized at times other than when the first solenoid 62 is energized.

In an instance when considered desirable, the apparatus can be employed to successively energize a single sign or writing by directly connecting the lead wires 63 and 65, as by a lead wire 81 shown in dotted lines in Fig. 7, and eliminating the second solenoid 64 and the parts actuated thereby, of course leaving the switch arm 56 engaged with one of the fixed contact elements 52, 53, 54 or 55, or directly connecting the lead wire 57 with one of the lead wires 48, 49, 50 or 51. Assuming the lead wires 63 and 65 in said Fig. 7 to be connected, the second solenoid 64 to be omitted, and the lead wires 57 and 51 to be and remain in conducting relation, the bulb 42 would become illuminated whenever the first solenoid 62 was energized and dead whenever said first solenoid was deenergized. It will be apparent that the principles of the invention are capable of employment to cause the same sign or writing, or different signs or writings, successively to be illuminated or otherwise made discernible.

What is claimed is:

A switch including a movable element, a frame constituted as an elongated element and transverse elements rigid with opposite ends of said elongated element in facing relation to each

other, alined first and second fluid conveying units supported by said frame each including a rigid tube having its exterior end secured in one of said transverse elements and a bellows supported upon the interior end of the rigid tube, a first pipe to lead from a source of fluid under pressure opening to a side wall of the rigid tube of said first fluid conveying unit in spaced relation to said transverse elements, a second pipe for conveying said fluid from a side wall of the rigid tube of the second fluid conveying unit in spaced relation to said transverse elements, there being a restricting orifice for flow of fluid between the bellows of said first and second fluid conveying units and access ports through said transverse elements contiguous with the exterior ends of said rigid tubes, closure plugs removably situated in said access ports, and a movable arm rigid with said movable element and secured to adjacent interior ends of said bellows to be operable in response to differential in pressure of fluid in and flow of fluid through the bellows of the first and second fluid conveying units to cause the movable contact element to be moved in one direction and in response to equalization of pressure in said bellows to cause said movable element to be moved in opposite direction.

GRANT A. SWANSON.
